ELECTRIC PSEUDO MACHINE GUN TOY

Jacob Schmidt, Newark, N. J.

Application March 20, 1940, Serial No. 324,928

6 Claims. (Cl. 46—112)

This invention relates to toys, more especially of electrically operated types, adapted for amusement purposes particularly for youths of boyhood age who enjoy toys simulative of warfare because of the noise and lights representing explosions.

It is an object of the invention to provide a pseudo toy gun of the rapid firing type, mounted preferably, but not necessarily, upon a railway car for easy transportation and capable of turning in any direction at will.

A further feature is in the provision of an electrical toy capable of giving forth sounds, accompanied by flashes of light, which represent an actual machine gun in operation.

Another purpose is to produce an automatic toy of the machine gun type that may be continuously operated, at different speeds, usable indoors or in the open air, with complete safety for indefinitely long periods of time.

These and other allied objects are attained by the novel design, construction and combination of parts hereinafter described and illustrated in the accompanying drawings, constituting an essential component of this disclosure, and in which:

Figure 1 is a side elevation view of an embodiment of the invention as mounted on a railway truck.

30. Figure 2 is a transverse sectional view taken on line 2—2 of Figure 1.

Figure 3 is a partial longitudinal sectional view looking on line 3—3 of Figure 1.

35. Figure 4 is a longitudinal sectional view taken substantially along the center of the invention.

Figure 5 is a partial plan and sectional view taken on line 5—5 of Figure 4.

Referring in greater detail to the drawings, the numeral 15 designates in general the outer rail 40 of an ordinary toy electric railway and 16 the electric current supplying rail as used to energize the trains passing thereover.

A platform 17 is provided with front and rear swivel trucks, respectively 18 and 19 each having two spaced pairs of wheels 20 to engage the rails; in addition the rear truck has a spring conductor 21 curved to make electrical contact with the third rail 16 as best seen in Figure 4.

The upper horizontal member of this conductor 55 is firmly secured to a block of insulation 22 by a rivet 23, which also rigidly clamps to the top of the block a resilient plate 24 having a notch 25 in its rear edge and extensions 26 provided with down turned, opposed edges 27—27'; the 55 front corners 28 are also bent downwardly.

A hollow circular bracket 30 is secured by screws 31 on the upper side of the platform 17, centrally in front of the block 22.

Above and resting on the bracket is plate 32 in which is secured a stud 33 revolvable in the bore of the bracket 30 in the manner of a pivot.

The plate 32 is secured centrally on the bottom of a turntable 34 having enclosing side and front walls 35 and 36, the rear being completely open for the entrance and exit of a toy operator 37, the entire casing being completely enclosed at the top by a fancifully formed roof 38; an upright transverse partition 39 separates the main portion of the casing into a major chamber for the mechanism and a smaller rear chamber for the operator.

Extending through the front wall 36 of the turn-table casing is a representation of a gun barrel 40 having a bore 41, counterbored at its breech, as at 41' and extending forward so that its muzzle is in vertical registration with the front edge of the platform 17, which is preferably provided at its front corners with means to support flag staffs 42.

An electric motor 45 is mounted on a bracket 46 fixed on the floor 34 of the turn-table in the main chamber. Mounted on the shaft 47 of the motor, is a gear wheel 48, in front of which is a disc 49 also free to revolve.

A smaller gear 50 is fixed to the rear face of the disc 49 and is driven by a pinion 51 meshed with an intermediate gear 52 having fixed alongside a pinion 53 meshed with the gear 48, thus materially increasing the speed of the disc 49 relative to the motor.

The disc 49 has a series of radial lobes 55 and is shaped to produce uniform curved recesses therebetween; these lobes are arranged to enter a correspondingly shaped depression in a flattened lug 56 supported on an upright spring 40 arm 57 fixed at its lower end to an insulate block 58 secured to the floor 34.

Set in the front face of the gear 48 are a series of studs 54, while in the disc 49 are an equal number of similar studs 59, arranged in offset relation to the studs in the gear.

A bracket, generally designated by the numeral 60, is fixed on the inner side of the front wall 36, its lower portion suited to serve as a bearing for a longitudinal shaft 61, passing 50 through the partition 39, where it is provided with a hand lever 62 conveniently arranged for manual operation.

A short transverse spindle 63 is also mounted in the bracket 60, just below the gun breach 55

opening 41', and shiftable therealong are a pair of spaced spring arms 65-66, carrying at their raised outer ends clappers 67-68 adapted to strike a sound producing element 69 fixed on the upper part of the bracket to produce a sharp detonating effect under the impetus of springs 70.

Set rigidly in the spring arms are rearwardly extending pins 72-73 extending into the plane of rotation of the studs 54 and 59 respectively.

The spring arm 65 is forked at its lower end and engaged therein is the semi-circular end of a lever 74, fixed on the shaft 61, by which the arm 65 may be shifted into and out of operative position relative to the sounder 69.

The electrical arrangement will now be described; as previously stated, when the device is used on a railway having a third or conductor rail, as 16, current is conveyed by the conductor 21 to the plate 24 and from thence to contact pins 75-76 set insulatively in the turn-table floor 34.

A conductor 77 leads to a plate 78 on the insulation block 58, thence to a spring conductor arm 79 arranged alongside the lug carrying arm 57.

Another conductor 80 extends between the plate 78 to a hand switch 82 having a lever 83 convenient of access to the operator 37.

Return current from the switch is by conductor 84 to a socket 85, set in the partition 39, and is receptive of the usual type of electric plug whereby current may be received from another source than that of the rail, the socket being connected by conductor 86 with an insulated central member 87.

From this focal point a conductor 88 leads to the motor 45, and another conductor 89 to a socket 90, fitting the breach of the gun 40 and fitted with a bulb 91 adapted to flash a ray of intense light through its muzzle.

Return current from the lamp is by conductor 92 to the base of the insulate spring arm 57, thence by conductor 93 to contact pin 76.

Return current from the motor 45 is by way of conductor 94 to plate 78. The focal plate is grounded by conductor 95, its terminal being held by screw 96 to the floor of the turn-table.

In operation, current being supplied through the rails or socket, the motor will start when the circuit is closed at switch 82. As the motor rotates the gear will turn, causing the lobes to spring the arm 57 into contact with the conductor arm 79 thereby closing the circuit to the light 91 and coincidentally the studs 54 strike the pins 72, vibrating the hammer arm 65 whereby the hammer strikes the sounder repeatedly a blow sufficient to produce a sound simulative of an explosion and the light to emit a ray in consonance with the sound so long as the switch is closed.

If a more rapid fire is desired, the lever 62 is moved to bring the plate carried studs 59 into operation with the pins 73 the rapidity of performance is doubled.

It will be noted the turn-table may be turned into different angular positions relative to the truck, or even removed bodily therefrom at will, thus enabling an extensive use of the toy.

Having thus described the invention and set forth the manner of its construction and use, what is claimed as new and sought to secure by Letters Patent, is:

1. A toy comprising a truck adapted to travel on rails, a turn-table pivoted on said truck, a casing for said turn-table having a relatively large

and small compartment, a pseudo gun extending in advance of the casing, said gun containing an electric light, a motor in the large compartment of said casing, means combined with said truck to energize said motor and light, a switch in the smaller compartment to make and break an electric circuit to said motor and light, a sounder in the main compartment, a gear train operative by said motor, a pair of clappers to strike said sounder, manual means to shift said clappers into and out of operative contact therewith, and means to cause said light to glow in consonance with the sound produced by said sounder.

2. In a sound and light producing toy, the combination of a railway having a third rail, a wheeled truck movable thereover, a collector to gather current from said third rail, a motor energized by the current, a toy gun, having an electric light bulb therein, means to control current to said motor and means actuated by the motor to energize said bulb at regular intermittences.

3. In a sound and light producing toy, the combination of a railway having a third rail, a wheeled truck movable thereover, a collector to gather current from said third rail, a motor energized by the current, a toy gun having an electric light bulb therein, a sounder to emit a noise simulative of the detonation of a gun, means combined with said motor to actuate said sounder and bulb simultaneously, means to control the rapidity of sound and bulb emanations, and a secondary source of current supply.

4. In a sound and light producing toy, the combination of a railway having a third rail, a wheeled truck movable thereover, and a collector to gather current from said third rail, a motor and gear driven by said motor having a series of spaced studs and disc connected by a gear train, said disc having a second series of studs, a detonating sounder, a pair of spaced hammers for said sounder, means to shift one of said hammers into and out of operative position, and means combined with said hammer engageable with said studs whereby the hammers are actuated.

5. In a toy, a device for producing repeated sounds simulative of gun discharges, comprising a stationary sounder, a pair of spring arms having strikers, resilient means to normally maintain said strikers out of contact with said sounder, pins set in said strikers, a drive wheel having spaced studs set in its face to contact the pins in one of said strikers at regularly spaced intervals, a drive disc having studs spaced intermediate the first named studs to contact the pins in the other striker, and means to shift the last named striker out of operative position relative to said sounder.

6. In a toy, a device for producing repeated sounds simulative of gun discharges, comprising a stationary sounder, a pair of spring arms having strikers, resilient means to normally maintain said strikers out of contact with said sounder, pins set in said strikers, a drive wheel having spaced studs set in its face to contact the pins in one of said strikers at regularly spaced intervals, a drive disc having studs spaced intermediate the first named studs to contact the pins in the other striker, means to rotate said disc in timed relation to said wheel, and means for moving said last named striker into and out of position to contact said sounder.

JACOB SCHMIDT.
